UNITED STATES PATENT OFFICE.

BRUCE BLACKBURN, OF LOS ANGELES, CALIFORNIA.

SCREENED WINDOW.

1,303,455.

Specification of Letters Patent. Patented May 13, 1919.

Application filed October 24, 1916. Serial No. 127,502.

To all whom it may concern:

Be it known that I, BRUCE BLACKBURN, a citizen of the United States, residing at Los Angeles, in the county of Los Angeles and 5 State of California, have invented a new and useful Screened Window, of which the following is a specification.

This invention relates to the art of screening openings such as windows and doors by 10 means of a flexible screen of wire cloth, and an object is to provide for a building, a screened opening, the mountings of which are concealed within the structure forming the opening and in which a wire cloth screen 15 is provided and arranged to be drawn into and withdrawn out of screening position.

The invention includes in combination a frame structure for the opening to be screened, a spring actuated roller screen fixture and housing and also the combined fixture and housing and other parts and combinations of parts as will more fully appear from the subjoined detail description.

An object of the invention is to provide a 25 frame structure and roller screen fixture in correlation to each other whereby it is made easy to install the fixture in and to remove it from the structure as occasion may require and to form a novel construction and combination of screened-window elements.

A further object of the invention is to provide a fixture that is adapted to be easily and readily inserted into and withdrawn from said structure, and which is adapted to 35 be engaged by the screen when closed, so as to close any opening due to unwinding the screen from the roller.

Another object is to construct a fixture that is adapted to be easily changed to a 40 slight extent so as to be adjusted to fit snugly in the opening in the frame prepared therefor, thus to accommodate slight inaccuracies of fit. Also to so construct the fixture that it is self-correcting as to adjustment in position in the housing; and to minimize the necessity of skilled labor for installing the screens.

In this invention I have produced a 45 disappearing roller screen housing with a deflected outer edge. One of the objects of deflecting the edge is to allow the slit in the housing cylinder to come on the outer side of said cylinder, thus allowing the screen to pass through the slit with minimum amount 55 of rubbing and also to allow the lower mar-

gin of the cylinder to extend toward the wire cloth so that when the screen is pulled entirely down, said margin is touched by the screen cloth thus excluding flies, etc. The deflected margin is so placed that when the 60 screen is allowed to wind clear up it acts as a stop and prevents the wire cloth from taking a short bend at the slide.

Other features, objects and advantages 65 may appear from the accompanying drawings, the subjoined detail description and the appended claims.

The fixture may be installed alternatively in a more or less concealed position and various modes of installation will be illustrated. 70

The accompanying drawings illustrate the invention.

Figure 1 is a fragmental sectional elevation of so much of the right side of a window 75 constructed in accordance with this invention as is necessary for an understanding of the application of the invention in a double-hung or weight window where it is desired to conceal the fixture in the cheapest and most complete way. The screen is shown 80 fully retracted.

Fig. 2 is a fragmental elevation of the 85 left side of the structure and fixture shown in Fig. 1 viewed from the inner side of the window.

Fig. 3 is a fragmental plan section in reduced scale on line x^x , Fig. 2.

Fig. 4 is a sectional elevation analogous to Fig. 1 showing the fixture installed in a structure in which the upper part of the fixture is concealed by a top stop in a double-hung window. 90

Fig. 5 is a fragmental elevation of the structure and fixture shown in Fig. 4 viewed 95 from the inner side.

Fig. 6 is a fragmental inner or front elevation showing one end of the housing detached and viewed from the inner side of the window.

Fig. 7 is a fragmental reverse view of the 100 part shown in Fig. 6.

Fig. 8 is a cross section of the housing, one of the end pieces or brackets of the fixture appearing in elevation.

Fig. 9 is an outside or end view of the fixture, showing in elevation, the end piece or bracket opposite the one shown in Figs. 6, 7 and 8, also showing the fastening tongues bent over thereon and the end of the angular gudgeon of the spring-actuated screen roller. 110

Fig. 10 is a fragmental development of one end of the slotted cylindrical housing wall with deflected edge and bead wings folded over. This view illustrates an end 5 of a stamping for forming the housing wall or screen case.

Fig. 11 is a diagram illustrating the folded edge strip or guide and stop at the lower edge of the wire screen.

10 Fig. 12 is a view analogous to Figs. 1 and 4 of a form in which the screen is concealed above the head jamb in a double hung window, the screen being arranged to pull down on the outside of the two sashes of the double 15 hung window.

Fig. 13 is a plan section detail on line x^{13} of the side of the window frame with sash and stops of the form shown in Figs. 12 and 14.

20 Fig. 14 is a view analogous to Figs. 1, 4 and 12 showing a double hung window with the screen on the outside. The cross sectional plan of this is the same as in Fig. 13.

Fig. 15 is a view analogous to Fig. 1 showing 25 a casement window with screen practically concealed in the head and running between the jambs and stops.

Fig. 16 is a fragmental plan section on line x^{16} of one side of the casement window 30 frame shown in Figs. 15 and 17.

Fig. 17 is a view analogous to Fig. 15 showing the screen and fixture practically concealed in a transom bar.

In the several views either the right or 35 left side of the window is shown; it being understood that the two sides are alike as to the jambs, stops and screenways which, as in usual constructions, are complementary to those shown.

40 Reference will first be made to the installation shown in Figs. 1, 2 and 3 in which the side jambs or pulley jambs 1 of the window frame is of well-known construction. The window casings 2, 3 and the blind stops 45 4 and split window stops 4' and 4'' are also of well-known construction, and are in fixed relation to the pulley jambs.

The head jamb is formed of a plurality of sections as 5, 6, 7. The main body 5 of the 50 head jamb is grooved as at 8, while the other sections, guards or closures 6, 7 are spaced apart at the mouth of a chamber formed partly by said sections 6, 7 and partly by the groove in the under side of the main head 55 jamb section 5. Sections 6, 7, are detachable and are spaced apart to leave an opening 9 into the chamber 8 which is adapted to accommodate a roller screen fixture above the level of the lower face of the head jamb.

60 The head jamb sections 6 and 7 partially close the mouth 9 of the chamber 8 which is sufficiently large to allow the housing for a roller screen to be inserted when the closure sections 6 and 7 are removed. The front de- 65 tachable section, guard or closure 7 of the

head jamb forms a head for the finishing members 4' of the divided window stop.

The opening 9 forms a screen-way extending from jamb to jamb and communicating at the ends with vertical screen-way grooves 70 10 extending between the window stop members 4', 4'' to the bottom 9'' of the opening to be screened.

The fixture includes a slotted housing comprising a nearly cylindrical case formed of 75 a volutoid sheet 11 constituting the surrounding wall of the housing and having a longitudinal slot or slot-like downward opening 12 in one side from which the woven wire screen fabric or sheet 13 may be drawn between complementary brackets 14, 14' that are preferably stamped from sheet metal and fixed to the ends of the sheet 11. On the ends of said sheet projecting tongues 15 are provided; the same being adapted to pass 80 through slits 16 cut in the brackets to accommodate said tongues. At one side of each bracket a rectangular flexible extension 17 is provided and the same is perforated with holes 18, 19, 20 punched outward from the 90 inside of the bracket to form countersinks for the heads of screws 21 that fasten the bracket to the side supports or pulley jambs 1.

The brackets are secured in place on the 95 cylindrical case by inserting the tongues 15 through the slits 16 and bending said tongues over on the outside of the bracket wall.

The roller is provided at its ends with the usual angular gudgeon 24 and the bracket 14 100 is provided with an angular slot 25 to receive the same. The centers of the brackets 14 and 14' are stamped to form the inwardly projecting bosses 26 punched to support said gudgeon 24 at one end of the roller and the 105 pivot pin 27 at the other end of the roller; the second bracket 14' being provided with a circular hole 28 in its boss 26 to seat said pivot pin.

To assemble the parts of the housing and 110 to then assemble the roller screen therein, the first bracket member 14' is first applied to one end of the cylindrical case, inserting the wings 15 through the slits 16, and then bending said wings over upon the outside of 115 said bracket member. Then the wire screen fabric is wound upon the roller and the spring given the appropriate tension in the usual way and the roller and screen are then inserted into the case allowing the fabric to 120 slip edgewise along the opening 12 therefor; and finally inserting the pivot pin 27 into the hole 28 therefor. Then the second bracket member 14 will be applied to the open end of the case, the angular gudgeon 125 24 being inserted into the seat 25 therefor and the tongues 15 being inserted through the slots 16 therefor, and bent over upon the outside of said bracket member, thus securing the bracket member on the sheet 11 and com- 130

pleteing the fixture which may then be inserted through the opening 9 into the chamber 8. One of the edges of the sheet 11 that constitutes the wall of the case, is deflected outwardly to form a straight lip 31 projecting outward from the cylindrical portion of the case, so that the slot 12 directly overhangs the screen-way grooves 10; and the stop 30 may contact with the lip 31 so that the free end of the wire fabric is thus prevented from being drawn into the case by the action of the roller springs. Therefore, the roller spring may be given any desired tension at the time of installing the screen in the housing, and there is no likelihood of the tension thus given being changed so long as the spring retains its original resiliency. When the fixture is installed as shown in Fig. 4 the lip 31 serves as a stationary stop to receive the movable stop or handle 30.

As is particularly shown in Fig. 11, the stop 30 preferably constitutes a longitudinal bend upon a metal strip which is further bent longitudinally so as to form flat outer sections 29 and 29' joined by the lower edge of the strip, and a flat intermediate section 29'', the lower edge of the screen 13 being securely clamped between the intermediate section and the outer sections, and the end of the metal strip so formed slidingly fitting in the screen-way grooves 10. It should also be noted that the stop is above the lower edge of the metal strip, so that, when the screen is raised to its stop-engaging position, any tendency of the stop 30 to tilt and to be drawn into the screen housing is prevented by the engagement of the ends of the metal strip with the screen-way groove.

The bracket 17, 17' are provided adjacent the lip 31 with a straight edge 32 extending vertically down from said lip and terminating at the lower edge 32' of the bracket, at right angles to said lower edge. The advantage of this construction is that when the fixture is mounted with its edge 32 in a vertical position the wire screen may be completely unrolled by pulling the free edge of the screen vertically and without rubbing the screen against the edge *e* at the margin of the slot 12. This is a desirable feature in the construction where the screen is mounted in the open as shown in Figs. 4 and 14.

In the form shown in Fig. 1, when the screen is retracted, the stop 30 engages the head jamb or closure section 7 instead of the lip 31, which lip in Fig. 1 rests upon the top of the jamb section 7. When it is desired to apply the fixture to a window frame, the vertical straight edge 32 is brought into a vertical position determined by bringing it into parallelism with the vertical edge of the side jamb or casing, and the bottom straight edge 32' of the two brackets

are brought to level position by locating 65 them at the same distance above the top of the side jambs or casings.

The edges 32, 32' of the bracket members are normal to each other and the edge 32 extends vertically downward from near the 70 edge of the lip 31 to the bottom horizontal edge 32'. To install the fixture, each of the side jambs 1 will first be marked with a horizontal line, not shown, each line being at the same distance from the head jamb, thus to 75 indicate the location of the base line 32' of the bracket as shown in the drawing. Then the fixture is brought into place with the base edges 32' of its brackets on the lines, thus marked but not shown in the drawings. 80 The vertical edges 32 are then brought to position equidistant from and in parallelism with the edges of the side jambs or casings. Then the screws 21 are inserted and driven home. In this way the time and labor of 85 setting the fixture is minimized; the rectangular members or legs 17, 17' of the brackets are laterally flexible, thus serving as gages to insure proper placing of the fixture.

In the form shown in Figs. 1 and 2 the 90 lip 31 rests on or is adjacent to the top of the head jamb section or closure 7 after the same has been brought into position and fastened by the screw 33.

After the brackets have been fastened in 95 place by screws 21 in the double hung window in Figs. 1, 4, 12 and 14, a bumper block 34 is fixed in place over the lower end of the bracket members 17 by means of screws 35, and the window stops 4" are applied over a portion of the bracket members 17. The inner faces 36 of the window stop members 4" form one side of the guide-way 10 and are arranged vertically beneath the inner edge *e* of the volutoid sheet 11. 105

In the form shown in Figs. 4 and 5 the head jamb section or closure 7" conceals only the upper portion of the case 11 and the lip 31 is open to view and serves as a stationary stop for the movable stop 30 of the flexible 110 screen 13.

In the form shown in Fig. 12 the head jamb section or closure 7" is a flat strip oblong in cross section extending across the window and fastened to the under-side of 115 the main head jamb section 5" which is rabbed at *r* to receive the section 7" and also the parting bead 37.

The head jamb section 7" is loose and removable, being caught under the rabbed portion of the head jamb section 5" and resting upon metal brackets 38 fixed by a screw 39 to the side jamb 1. 120

In Fig. 12 the fixture is arranged with its housing opening 12 presented toward the outside head casing 40 above the lower edge of the same. The head jamb section 7" can be inserted and removed from its position 125

below the fixture by first lowering the window sash 41 and then simply removing the screws 39 and the brackets 38.

In the form shown in Fig. 14 the cylindrical portion of the volutoid case is set out beyond the outer head casing 42. It may be gained in or housed in the window structure more or less depending upon the thickness of the casing and of the walls. The 10 cylindrical portion of the volutoid shell is exposed to the weather and protects the opening 12 which is presented inward toward the window sash 41. The runway 10 is made in this form by a single outer stop 15 43 and the usual blind stop 4, said outer stop 43 being fastened against the inner edge of the outside casing 44.

In the form shown in Fig. 15 a construction 20 for mounting a screen in connection with a casement window is shown. The casement window 45 in this view is arranged to open outwardly. The main head jamb section 5''' is provided with a groove 46 in which the fixture case is mounted, the lower 25 edge of the lip 31 being flush with the lower face of said head jamb section 5''' and resting on the head jamb section of closure 7''. The head jamb section 6''' extends underneath the volutoid shell and is supported at 30 its ends by a stop 47 which covers the major portion of the lower ends of the bracket members 17. An inside stop 48 extends under and supports the ends of the head jamb section or closure 7''. The guide-way 10 is 35 formed between the stops 47 and 48 fastened to the side jambs 1.

In Fig. 17 the transom bar 54 takes the place of the main head jamb section 5''' and is provided with a groove 49 in which the 40 fixture is mounted in a manner analogous to that shown in Fig. 15.

The manner of installing the invention in these different forms is apparent from the foregoing description.

45 The volutoid case is preferably constructed mainly as a cylindrical shell and in the views except Fig. 10, the character 11 is applied to the cylindrical part and in Fig. 10 it is applied to the part that becomes cylindrical in the completed fixture.

By combining the semi-cylindrical portion thus marked, with the outwardly deflected lip 31 the required rigidity is secured in the longitudinally slotted housing which 55 allows the edge of the screen to be manipulated and drawn from and wound onto the roller 22 with a minimized liability of rubbing the screen; at the same time avoiding sharp bending of the screen and allowing 60 the stop 30 to be intercepted without likelihood of wedging.

In practice, when the screen is drawn down to the window sill, not shown, the screen 13 will be so far unwound from the 65 roller 22 that it will engage the edge $\hat{e}$ thus

closing the slot against the admission of insects that might otherwise crawl into the housing and around the screen on the roller and thence in front of the screen through the slit into the building intended to be protected. 70

By arranging the edge e between the vertical edge 32 and a vertical line f drawn downward from the front edge of the roller in parallelism with the vertical edge 32, the 75 operation above set forth is effectual to exclude the flies, and the screen runs free from the edge during the latter part of the opening movement and the first part of the closing movement of the screen. The nearer the 80 edge e is to the vertical line f drawn from the front edge of the roller when the edge 32 is vertical, the greater will be the screen travel without rubbing; and it is understood that the edge e may be located so far from the vertical edge 32 that when the screen is pulled down to the window sill, not shown, said screen may not touch the edge e . This might result from having considerably more 85 screen on the roller than is required for 90 closing the window opening and it is therefore desirable that the amount of screen on the roller should be only ample for closing the opening, and that the edge e be located just in front of a line drawn from the front 95 edge of the roller in parallelism with the vertical edge 32, as is most clearly shown in Fig. 1.

By reason of the bendable tongues 15 extending through the slits 16 it is only necessary in order to remove the roller and attached screen for the purpose of repair and for any other purpose, to simply straighten the tongues 15 so that the bracket may be withdrawn from the end of the case, thus 100 leaving the roller free to be withdrawn from the case to which it may again be returned and the bracket again fastened in place as before. 105

It is thus seen that I have provided a 110 practically concealed roller screen 22, 13 in the head jamb of a window structure and have also provided a window structure with a head jamb section grooved on its under side and have combined therewith a disappearing 115 roller screen concealed in said grooved section by detachable head jamb sections as at 6, 7 and their equivalents shown in Figs. 12, 15 and 17 whereby the roller screen and its housing are easily installed and removed. 120

I claim:—

1. The combination with side jambs; of main, front and rear head jamb sections, the front and rear sections being spaced apart to form an opening; one of said latter two sections having a vertical edge presented toward said opening and forming a removable guard for said opening, there being a space at said vertical edge to form a screen-way between said edge and the other of the latter 125 130

two sections; and a roller screen housing comprising a case and end brackets, said case having a longitudinal slot with a deflected lip at one edge of said slot resting on the 5 head jamb section having the vertical edge, above said vertical edge thereof; brackets at the ends of said housing, each having a vertical edge above the vertical edge of said head jamb section, and means to fasten the 10 brackets to the side jambs.

2. The combination with side jambs; of a head jamb constructed with front and back sections spaced apart to form an opening; one of the sections constituting a removable 15 guard for said opening; said sections being arranged to provide between them a screen-way through which a screen may be drawn; a roller screen housing insertible through said opening, and concealed by said guard; said housing being provided with end 20 brackets and comprising a cylindrical slotted case having a deflected edge; said brackets being provided below said deflected edge with a vertical edge to serve as a gage for 25 locating the housing relative to said sections.

3. The combination with a window casing having a head jamb and side jambs provided with screen-way grooves, of a housing having at one side a longitudinal slot and an 30 outwardly deflected, straight lip at one edge of the slot; a spring operated roller in the housing, a screen on said roller and a strip fastened upon the lower end of the screen and bent longitudinally so as to form flat

outer sections joined by the lower edge of 35 the strip, the ends of the strip slidably fitting in the screen-way grooves, and the strip also being provided with a longitudinal bend forming a handle and a stop above the lower edge of the strip to operate the screen and to 40 engage the lip.

4. The combination with a screen roller and a screen thereon, of a housing provided with a bracket having a straight, vertical 45 edge and also provided with a slot having at one side an edge extending to the straight edge and at the other side an edge located between said vertical edge and a line drawn from the front edge of the roller in parallelism with said straight edge.

5. The combination with a screen roller and a screen thereon; of a housing for said roller and screen; said housing being provided with a slot through which said screen may be drawn from the roller; and a guide 50 for the screen, said guide being so located relatively to an edge of the housing at one side of the slot that only when the screen is drawn into the guide and mainly unwound from the roller the screen will contact with said edge to exclude insects from the housing.

In testimony whereof I have hereunto set my hand at Los Angeles, California, this 17th day of October, 1916.

BRUCE BLACKBURN.

In presence of—
JAMES R. TOWNSEND.
